PAPER CONTAINER

Application filed December 19, 1929. Serial No. 415,208.

Our invention relates to improvements in paper containers of the truncated cone type and the object of the invention is to devise a paper container of this type which is self contained and made entirely of paper and in which the cover or closure is integral with the main body of the container and is locked in the closed position.

Our invention consists of a circular bottom, 10 a body and closure integrally formed from a blank and preferably wound upon itself to form a double wall having its edges overlapping, the bottom of the wall being connected to the bottom proper by a suitable interlocking rim and the body being flattened gradually from bottom to top to a top edge over which the integrally formed closure folds and locks as hereinafter more particularly described.

20 Figure 1 is a side view of the container with the form of the closure shown in dotted lines and the closure on one side in full lines.

Figure 2 is a side view of the container 25 from the opposite side.

Figure 3 is a vertical section through the container with the closure folded into the closed position.

Figure 4 is a detail of the blank from 30 which the body and closure is formed.

Figure 5 is a plan view, and

Figure 6 is a detail of the closure.

In the drawing like characters of reference indicate corresponding parts.

35 1 is the blank of paper of arc-shape form with substantially curved top and bottom edges and straight ends. 1' is an upward extension of a blank provided with wings 1² having the notches 1³. The extension 1' is 40 designed to be folded on the perforated line 2 and also on the perforated lines 3, 3.

4 4 is the bottom made of paper in circular form with depending flanges 4' which interlock when the container is formed up with 45 flanges formed at the bottom edge of the blank 1 to form a reinforcing rim at the bottom of the container. This rim does not form part of our present invention and we therefore do not particularly describe it.

50 In forming up the main body of the con-

tainer we wind it upon itself to form a double wall as indicated in Figs. 3 and 6, the outer edge overlapping the inner edge as indicated in the latter figure, and it is the bottom edge of this double wall which forms with the flange at the bottom the reinforced bottom rim. 55

The container, it will be noticed, is substantially the same width from top to bottom looking at one diameter in cross-sectional plan but is, looking at the diameter at right angles to the above diameter, tapered from top to bottom to a point in vertical section, but terminates in a straight edge as indicated in Figs. 1 and 2. In short, the container is of a flattened truncated cone form, as will clearly appear in reference to Figs. 1, 2 and 3, and the plan shown in Fig. 5. 60

The extension 1' is folded over on the dotted line 2 and over the straight edge of 70 the flattened top as indicated in Figs. 1 and 3. The wings 1² are folded laterally on the dotted lines 3 onto the opposite flattened side where they may be connected together by any suitable fastening such as the coacting slits 1³ formed in the wings 1², see Figs. 2 and 4. 75

Such a container as we have described is a unitary one as far as the main body and closure is concerned and is suitable for various commodities particularly where it is not necessary to have such commodities hermetically sealed. 80

It will be understood that the form of the container and its closure may be changed to 85 some extent without departing from the spirit of the invention and yet come within the scope of the claims.

What we claim as our invention is:

1. A container comprising a suitable bottom, a body connected thereto by a suitable rim and of a flattened truncated form, terminating at the top in straight opposing edges, the centre of one flattened side having an extension designed to be folded over the opposite edge of the opposing flattened side and means forming part of the extension for holding it in the turned down position. 95

2. A container comprising a suitable bottom, a body connected thereto by a suitable 100

rim and of a flattened truncated form, terminating at the top in straight opposing edges, the centre of one flattened side having an extension designed to be folded over the opposite edge of the opposing flattened side, and lateral extending wings designed to be folded on the opposite side of the container to the extension and means for holding them in the folded position.
